UNITED STATES PATENT OFFICE.

HARRIET K. ELY, OF NEW YORK, N. Y.

DESIGN FOR PEN-RACKS.

Specification forming part of Design No. **11,258**, dated June 24, 1879; application filed January 16, 1879.
[Term of patent 3½ years.]

To all whom it may concern:

Be it known that I, HARRIET K. ELY, of the city, county, and State of New York, have produced a new and original Design for a Pen-Rack, of which the following is a full, clear, and exact description, reference being had to the accompanying drawings.

Figure 1 in the drawings presents a front view of my newly-designed pen-rack, and Fig. 2 is a side view thereof.

It will be seen that the frame or body of the pen-rack is designed to represent a horseshoe, the headed nails of which project from the grooved face thereof.

The rack is represented as being in an easy inclined position by a central leg extending from the back of the horseshoe at an opposite inclination, and which is designed to represent the fore leg of a horse, as shown, thus giving a harmonious effect. The face of the

shoe is smooth, without the usual calks, as shown, and the level surface is thus well adapted to receive painted decorations, to impart an ornate tone to the design, a motto being usually inscribed over the arched top with flowers or tracery upon each branch of the shoe, the whole design thus giving a novel and pleasing effect.

What I claim is—

A design for a pen-rack, consisting of a horseshoe-shaped frame and rack pegs projecting therefrom in the shape of the headed ends of horseshoe-nails, and a central supporting-leg behind, representing the fore leg of a horse, substantially as herein shown and described.

HARRIET K. ELY.
